UNITED STATES PATENT OFFICE.

SIMEON E. KINNAN, OF MIDDLEBURG, FLORIDA.

BOTTLE-CAP.

SPECIFICATION forming part of Letters Patent No. 591,849, dated October 19, 1897.

Application filed June 1, 1896. Serial No. 593,801. (No model.)

To all whom it may concern:

Be it known that I, SIMEON E. KINNAN, a citizen of the United States, residing at Middleburg, in the county of Clay and State of Florida, have invented certain new and useful Improvements in Bottle-Caps; and I do hereby declare the following to be a full, clear, and exact description of the invention, such as will enable others skilled in the art to which it appertains to make and use the same.

My invention relates to bottle-caps.

My object is to provide a bottle-cap of simple and cheap construction, which will comprise such improved features that, after being once applied to the bottle-neck, said cap will lock and so seal the bottle that the contents thereof can only be obtained by breaking the neck.

The foregoing object is accomplished by the employment of a bottle-cap of improved construction, as will appear more fully hereinafter, and the novel features thereof be recited in the appended claims.

In the accompanying drawings, Figure 1 is a side elevation of a modification, showing the cap removed; Fig. 2, a sectional elevation of the cap, and Fig. 3 a sectional side elevation of the complete modification; Fig. 4, a horizontal cross-section of Fig. 2.

The bottle-neck is provided with the usual flange 3. I employ a locking-barrel 9, made of spring metal and having tapering ends 10 and 11, which rest against the flange of the neck and the bottle-body. This locking-barrel is provided with screw-threads 12 and is longitudinally slotted at 13. A tongue 14 is struck up from one of the edges defining the slit. The locking-barrel is notched at 15 to receive one end of a string or cord 15. I employ a cylindrical glass locking-cap 16, having inner screw-threads 17, which are adapted for engagement with the threads on the locking-barrel. This locking-cap is provided with four inner longitudinal grooves 18, which are situated at approximately ninety

degrees apart and are adapted to receive the locking-tongue 14.

After the bottle has been filled and corked, the locking-barrel placed in position, and the string inserted in the notch the locking-cap is screwed onto the locking-barrel, the operator meanwhile holding the string or cord 15 to prevent said locking-barrel from turning. As the cap is screwed on the tongue 14 55 clicks into and out of the longitudinal grooves of the cap until, when the cap is in proper position, the tongue engages with one of the grooves. The string is then cut off by the cap. The locking barrel and cap will now 60 turn together and cannot be separated without damaging or destroying one or the other, thus preventing refilling of the bottle.

Having thus described the invention, what is claimed as new is—

1. The combination with a bottle-neck, of a barrel consisting of a screw-threaded piece of spring material bent around the neck and having separated ends, being also provided with a tongue, and a locking-cap provided 70 with grooves adapted to receive the tongue and which cap screws onto the locking-barrel.

2. The combination with a bottle-neck, of a locking-barrel located on said neck, a locking-cap adapted to engage with said barrel, 75 and a cord connected to the barrel and whereby the latter may be held when the cap is being connected thereto.

3. The combination with a bottle-neck, of a screw-threaded locking-barrel located on 80 the neck, a flexible, severable connection secured to said locking-barrel whereby the same may be prevented from turning, and a locking-cap adapted to be screwed on the locking-barrel and sever the said connection.

In testimony whereof I have signed this specification in the presence of two subscribing witnesses.

SIMEON E. KINNAN.
